UNITED STATES PATENT OFFICE

RALPH F. THOMPSON, OF EAST LIVERPOOL, OHIO; SARAH MACGREGOR THOMPSON, ADMINISTRATRIX OF SAID RALPH F. THOMPSON, DECEASED, ASSIGNOR TO SARAH MACGREGOR THOMPSON, OF SEWICKLEY, PENNSYLVANIA

ELECTROMAGNETIC RELEASE VALVE

Application filed December 21, 1929. Serial No. 415,849.

The present invention relates to electromagnetically controlled fluid devices for operating electric switches and the like and particularly relates to improvements in devices 5 generally termed electro-pneumatic contactors such as are commonly employed in electric railway substations, although said devices may be employed for other purposes, and in the valves, termed magnet-valves, 10 which operate these contactors.

The principal object of my invention is to provide an electromagnetically controlled fluid device for automatically opening switches at an electric railway substation to better protect the equipment of such substations against abnormal conditions, more particularly, to protect the synchronous converter against flash-overs, due to direct current short-circuits and overloads.

Another object of my invention is to provide an electromagnetically controlled fluid device for opening switches at a railway substation in a shorter interval of time than is required for the opening of the circuit breakers usually employed on the trolley cars which are fed from the substation.

Another object of my invention is to provide an electromagnetic release valve for releasing a fluid under pressure from within a vessel, which will release the fluid more quickly than devices of the prior art have been capable of doing.

A further object of my invention is to provide an electromagnetically controlled fluid device for opening electric switches, which will insure a very rapid opening of the switches when abnormal conditions occur in the circuits in which the switches are located.

Another object is to provide an improved construction of a magnet valve which will prevent the valve from sticking, particularly the magnet armature thereof, thereby preventing considerable damage to substation equipment.

Another object is to provide an electromagnetic release valve and magnet-valves which will function more efficiently and which will require less control energy for 50 their operation, thereby reducing the maxi-

mum demand on the current control supply of a substation and eliminating storage batteries, which are generally found necessary in connection with the control current-supply to maintain the required voltage, to effect a 55 material saving in the cost of maintenance of the substation.

A still further object is to provide a magnet-valve which is sufficiently sensitive in itself to eliminate the use of delicate relays 60 which have been necessary heretofore.

Other objects and advantages will appear more fully hereinafter from the following detailed description together with the drawings, in which:

Fig. 1 is a sectional view of the electromagnetic release valve of my invention and my improved magnet for a magnet-valve;

Fig. 2 is a detailed front view of the interlock switch mechanism; and

Fig. 3 is a schematic electrical diagram of an elementary substation circuit showing the location of the valve of my invention therein.

The type of switch generally used heretofore, known as an electro-pneumatic contactor, comprises a cylinder mounted in a vertical position, the lower head of which is provided with a projection which forms a support for a magnetically operated valve and this head, together with the valve supporting projection, is generally designated as a valve bracket. The magnetically operated valve functions to admit compressed air, or other fluid under pressure, to and to exhaust it from the cylinder and is known as a magnet valve. A piston is normally held in a vertically raised position in the cylinder by compressed air, or other fluid admitted to the cylinder, and to the external end of the piston or piston rod is attached one of the contacts of the contactor which keeps the contactor closed when the piston is in its normally raised position. When a predetermined over-load occurs on the line or a short-circuit on the feeders, the magnet valve is actuated to exhaust the fluid from the cylinder, thereby permitting the piston to be forced downwardly by the action of a heavy spring thus causing the contactor switch to open. The magnet-valve sometimes becomes

65

70

75

80

85

90

95

100

inoperative due to the sticking of the parts, particularly the magnet armature. This failure, while always causing an interruption of the power supply to the railway, also frequently causes considerable damage to substation equipment. The application of my invention to the magnet-valve eliminates the possibility of such sticking.

The above description may be more clearly followed from Fig. 1, in which the upper half of the device, i. e., above the supports 58 corresponds to a pneumatic contactor cylinder and piston of the prior art; a novel feature of my invention being in providing an exhaust port in the bottom of the cylinder in addition to the exhaust port 61 provided in the magnet valve at the right supported on the bracket 57, and in providing my improved electromagnet to open and close said port.

It was found that in applying the devices of the prior art for the opening of electrical contractors, the opening was not sufficiently rapid and provided a comparatively slow release of the fluid from the cylinder and therefore provided a cushioning effect for the piston on its downward motion. This slow release action was disadvantageous in that flash-overs were produced on the synchronous converter at the substation, due to the fact that the circuit breakers on a trolley car, fed from the substation and on which a short-circuit would occur, would open sooner than the load limiting contactor at the substation, thereby causing an excessively large current to be broken which would cause flash-overs. By providing my improved release valve, which provides a very rapid action and opens the load limiting contactor before the circuit breakers on the car are opened, the short-circuit current is reduced by virtue of heavy grid resistors which are connected across the contactor, so that the load on the line is largely reduced and when the circuit breakers on the car do function, a much smaller current is broken, thereby preventing the flash-overs on the synchronous converter. To produce this quick action, I have provided an exhaust port in the bottom of the cylinder which permits the fluid to be exhausted from the cylinder more rapidly than through the exhaust port provided in the magnet valve and an improved electromagnet for opening and closing said port.

Referring to Fig. 1, my device in its entirety comprises the usual cylinder 1 provided with a piston 2 adapted to be moved in the cylinder against the action of the spring 40 by the fluid under pressure entering through the inlet port 4 and the valve 23 through the passage 3 to the piston 2. The admission of the fluid from the inlet port 4 to the passage 3 is controlled by the valve 23 which is held open by means of the electromagnetic device attached to the valve stem 26 and which comprises electromagnet 17 en-

ergized by means of a shunt coil 20. The electromagnet is of the iron-clad flat-coil type, the tractive power of which is relatively small but the holding power is relatively large. Normally, the shunt coil 20 is energized, thereby energizing the magnet 17, which, in turn, attracts the flat disk armature 16. The armature 16 is mounted on a sleeve 15 through which the extension 34 of the valve stem 22 of the valve 18 is adapted to slide. The valve 18 is kept on its seat by the action of the spring 36 which is compressed against the valve stem by the action of the armature 16 when it is in magnetic contact with the magnet 17. The nuts 38 are provided for varying the compression of the spring 36, that is, to vary its initial compression. When the armature 16 forces the sleeve 15 down on the spring 36, the spring is given its final compression, sealing the valve 18 by transferring the pressure of the spring from the nuts 38 to the valve seat and leaving a small gap between the nuts and the armature 16. The valve 18 is normally closed when the valve 23 is held open, since they are integrally united by the valve stem 26. The function of the shunt coil 20 is to normally hold the armature 16 in contact with the magnet 17, thereby maintaining the valve 18 closed, so as to prevent the fluid under pressure escaping through the exhaust port 61. A cross-head 60 is attached to the end of the piston rod 62 of piston 2 which maintains the movable contact of the electrical contactor in a closed position when the piston is in its raised position, as indicated in the drawings. In addition to the shunt coil 20, I provide a series coil 63 comprising one turn of comparatively heavy wire wound around the core of magnet 17 or around the coil 20 and energized in an opposite direction to the windings of the coil 20. Normally, the coil 63 is not provided with sufficient energy to counteract the flux of the coil 20, because it carries only a very small portion of the load current. However, when the load on the line rises to a predetermined over-load (Fig. 3), a comparatively large current is caused to flow through the series coil and this current counteracts the action of coil 20, thereby demagnetizing the magnet 17 and permitting the spring 36 to move the armature 16 which then releases the compression of the spring 36, thus permitting the fluid under pressure to raise the valve 18 and permit the fluid to be exhausted through the port 61. Valve 18 is slightly accelerated by a momentary repulsion between the magnet 17 and armature 16. As soon as the fluid is exhausted, the piston 2 is caused to move downward by the action of the spring 40, carrying with it the cross-head 60 and the movable contact of the contactor or switch, thereby breaking the circuit of the line. This action in itself is sufficient only when over-loads occur on the

line, but in the case of short-circuits on trolley cars fed by the line, additional means is required to speed up the release action of the piston so that the contactor may be 5 opened sooner than the circuit breakers are tripped on the trolley car. To accomplish this, I provide an additional exhaust port 5 and a valve 6 for keeping it closed in its normal position, the valve being 10 held against its seat by the action of the spring 14. The spring 14 is given its initial compression by means of the head 7 of the sleeve 41 which is threaded in the disk armature 8. The compression of the spring 15 14 may be adjusted by means of nuts 42 which are attached to the end of the valve stem 9. The nuts 50 are for the purpose of affording a larger bearing surface for the pressure of nuts 42 against the end of sleeve 41. A final 20 compression is given to the spring 14 by means of the armature 8 when it is attracted by the magnet 10. The magnet 10 is similar to the magnet 17 of the magnet-valve and is also provided with a shunt coil 19 and a 25 series coil 64, both of which function in exactly the same manner as coils 20 and 63. However, coil 64 is connected across an inductive shunt 72, as indicated in Fig. 3.

The inductive shunt does not materially affect 30 the division of normal load current between the bus and the series coil 64. The resistance of the section of bus shunted by the series coil and the resistance of the series coil 64 with its connections to the bus are 35 so proportioned that the load current passing through the series coil 64 is not sufficient to counteract the effect of the current in shunt coil 19 and demagnetize the magnet 10 until the load is permitted to reach an amount 40 greater than that at which the magnet valve (17-18) is adjusted to open the contactor 73, that is, at normal over-loads the magnet valve 17-18 operates to open the contactor 73 before the load rises to an amount sufficient 45 to effect the demagnetization of magnet 10 and open the release valve 6. However, when a sudden and large rush of current occurs, as on the occurrence of a short-circuit on the feeders, the reactance of the 50 inductive shunt momentarily forces a comparatively large current through the coil 64, counteracting the current in coil 19, demagnetizing the magnet 10 and releasing its armature 8, thereby releasing the valve 6 and 55 permitting it to be forcibly opened by the air pressure from the cylinder 1. The motion of the valve 6 is also accelerated by a momentary repulsion between the armature 8 and the magnet 10 due to the sudden rush 60 of current in coil 64.

Normally, the armature 8 is in contact with the magnet 10 by the action of the coil 19 to keep the valve stem 9 in a raised position, thereby holding the valve 6 against its 65 seat and keeping the exhaust port 5 closed.

The electromagnet comprising the magnet 10 and the coil 19 is of the iron-clad flat-coil type enclosed in a shell and having a weak tractive power but a comparatively high holding power similar to magnet 17 and coil 20. By using this form of electromagnet and a light disk armature, a smaller amount of control current is required to hold the armature 8 against the magnet than is required in the usual form of electromagnet used in control work in which a large mass of iron and a relatively long coil are used, making it difficult to demagnetize the core quickly. The low tractive power of the electromagnet is compensated for by providing a light restoring spring 13. The force of spring 13 is so small that it will barely sustain the weight of the armature and the parts attached to it and will not materially oppose the opening of the valve 6. The adjustment of this spring may be made by the screw 27 threaded in the iron base 51 and locked by lock nut 28. The purpose of the restoring spring 13 is to restore the armature 8 into close proximity to the magnet 10 after an opening has occurred, thereby giving the electromagnet only the function of giving the spring 14 its final compression which may be approximately .02 of an inch. In other words, the electromagnet is relieved of the function of lifting the weight of the armature and only has to overcome the final compressing force on the spring 14 to close the valve 6. The force of the spring 14 is somewhat greater than that necessary to seat the valve 6 against the fluid pressure from within the cylinder. After the armature 8 is in contact with the magnet 10, it can be easily held and with a small fraction of the ampere turns required to pull it into contact against the action of spring 14. This is taken advantage of to save control energy and, more particularly, to reduce the ampere turns to permit a quicker release of the armature 8 by inserting a resistance r in series with the shunt coil 19 of the magnet by means of the interlock switch 81 (Fig. 3) when the contactor closes, thereby reducing the current to about one-tenth of the amount required during the closing operation of the release valve. A similar resistance r_1 with interlock 84 is provided for the coil 19. Another interlock switch 34 is provided in series with the shunt coil 20 of the magnet-valve by means of the terminals 45 and 46 (as shown in Fig. 1 and Fig. 3) to prevent any possibility of the magnet-valve becoming energized and closing the valve 18 and admitting fluid to the cylinder before the release valve 6 is sealed by the armature 8 coming in contact with its magnet 10 and also to assure the demagnetization of the magnet-valve when the release valve opens to avoid the fluid being forced through the valve 23 from the inlet port 4. The interlock switch 34 comprises a lever 11 piv-

oted at 65 and having a shoulder 66 which is actuated by the armature 8 when the armature is in contact with the magnet 10 (Figs. 1 and 2). The section 44 is of insulating material and a flexible connection 67 is provided from the lower brass end 68 of the lever 11 to the binding post 45. The other connection is made to post 46 from the stationary contact bracket 47. The purpose of the lever 10 of the interlock switch is to multiply the movement produced by the armature 8 to close contacts 34. It might be possible under some conditions for the armature 8 to fail to pull in the last small fraction of an inch necessary to transfer the pressure of the compression spring 14 from the nut 42 to the valve seat of valve 6 and in such a case, the magnet-valve must not be permitted to admit fluid to the cylinder. Therefore, the interlock switch 34 must be operated by the last small fraction of an inch of travel of the armature and this fraction may be about .02 of an inch. The adjusting screw 12 is provided for the adjustment of the stationary contact 21. The insulation 44 is in two strips, one secured to either side of the brass end pieces with a small space between them forming a slot as indicated in Fig. 2. Through this slot, the flat stud 33 passes to act as a guide for the interlock arm. Spring 32 opens the interlock when armature 8 falls away from the shoulder 66 of the lever 11. The strips 52, between which is mounted the iron bracket 51, are of insulating material, such as some phenol condensation product, hard rubber and the like. The screw 35 is a filister-head screw and is provided for attaching the terminal block 29 to the device. The terminals 30 and 31 are one of the terminals of each of the series coils 64 and 63, respectively. The terminals of the shunt coils are not known.

In the case of the magnet-valve, the magnet 17 is screwed into a portion of a magnet-valve and prior art at 54. Spring 25 of the magnet-valve is for the purpose of raising the valve 24 against its seat when the magnet 17 has been demagnetized and is held against the valve 24 by means of the retaining nut 55.

An additional feature of my invention is the provision of an improved armature for the electromagnets of both the magnet-valve and the release valve which is so constructed that any tendency for the armature to become cocked, thereby causing the valves to stick, is avoided. This is accomplished first, by providing the arrangement of the sleeves to which the flat disk armatures are attached and through which the valves and valve stems are guided as a unit and constructing this assembly so that its length is greater than its diameter, and then making the sleeves and armatures integral so that the armatures in all positions will be held rigidly parallel to

the faces of their magnets, for the purpose of preventing binding due to any unequal attraction between the armatures and their magnets. In the magnet-valves of the prior art, the armature generally consisted of a relatively short hollow cylinder closed at one end and which was not made integral with the valve stem and the armature was merely poised on top of the valve stem; these conditions resulted in cocking and sticking. The armature did not come in direct contact with the core of the magnet and, therefore, had very little holding power. For this reason, full current had to be maintained through the holding coil and even then the armature would be released if the control voltage dropped about fifteen percent, while actually, it should be held at least until the substation shuts down automatically on low voltage, the shutting-down point being about twenty percent below normal voltage. With my improved electromagnet, the current through the coil of the electromagnet is reduced to about one-tenth of the amount required to close it and the magnet will hold the armature until the control voltage drops to thirty percent below normal. These features assure more efficient operation of the valves and all tendency of the valves to stick is avoided, since the sleeve and valve stem assembly has, as a unit, a much greater length than diameter and, therefore, does not have a tendency to cock and bind in sliding through the hole in the magnet as did the cylindrical armature of the prior art, with diameters greater than their lengths.

Referring to Fig. 3, which shows a feeder circuit with the electromagnetic release valve of my invention connected therein, the release valve and cylinder are represented by the numeral 83 and the magnet-valve by the numeral 82. The synchronous converter 69 is supplied with alternating current from a line and one of the output terminals is grounded as is customary in railway feeder circuits. The other terminal leads to the feeders indicated at the right and the line is protected at various places by the contactors 70, 73, 74, 77 and 78. The contactor 73 is the one which is operated by my improved electromagnetic release valve and is shunted by the heavy grid resistances R which substantially reduce the short-circuit current when the contactor 73 is opened, thereby reducing the short-circuit load before feeder contactor 77 or 78 can open and thus preventing flash-overs on the synchronous converter 69. The series coil 64 is provided with an inductive shunt 72 across which it is connected, the function of which is to momentarily cause a large current to pass through the coil 64 when a short-circuit occurs to demagnetize the core of the electromagnet by counteracting the magnetic flux produced by the shunt coil 19. The se-

ries coil 63 is not provided with a separate inductive shunt, but depends upon the voltage drop through a part of the bus, i. e., the current divides through the series coil 5 63 and the section of bus and is inversely proportioned to their resistances and affords a means for adjusting the magnet-valve to a predetermined over-load. The numeral 10 81 indicates the interlock switch which is operated simultaneously with the contactor 73 to insert a resistance r in series with the coil 19 after the contactor is closed, thereby reducing the current through the coil 19 so that the magnetic flux produced by it is reduced, which may be more easily opposed by the magnetic flux from the series coil 64. In addition to the resistance r in series with coil 19, there is also a resistance r_1 in series with coil 20 and each resistance r and r_1 is 15 shunted by the interlocks 81 and 84, i. e., the interlocks short-circuit the resistances when the contactor is open and leave them in circuit with the coils when the contactor is closed. 20

25 The circuit of the interlock switch 34 is also shown and is in series with the shunt coil 20, so that the coil cannot be energized until the valve of the release valve 83 is closed as has been explained hereinbefore. The shunt 30 coils 19 and 20 of the release valve 83 and magnet-valve 82, respectively, are energized from a control current supply or control circuit as are the coils 86 and 87 of the magnet-valves 71 and 85. The control is generally provided from a current rectifying device (not shown), at 32 volts and due to poor voltage regulation of the rectifying device, it was necessary heretofore to employ a storage battery floating on the control 40 circuit. The use of my invention reduces the amount of control energy required for the substation apparatus to such an extent that the storage battery is not necessary, thereby effecting a material saving in the 45 cost of maintenance and replacement of such batteries at substations.

The series windings 90 and 91 of the magnet valves 79 and 80 of the feeder contactors 77 and 78 are provided with inductive shunts 50 75 and 76 while the shunt coils 88 and 89 are energized from the line through bridging resistances R_1 and R_2 . In series with shunt coils 88 and 89 are adjustable resistances r_2 and r_3 , adjusted to enable the shunt 55 coils 88 and 89 to overcome the flux due to the small current in the series coils 90 and 91 when the short-circuit current is reduced to a predetermined amount and thus cause contactors 77 and 78 to reclose. Resistances 60 r_4 and r_5 are provided also in series with coils 88 and 89 to reduce the amount of current flowing therein after the contactors 77 and 78 are closed. While the contactors are open, the resistances are shunted by their respective interlocks which are actuated by

the magnet valves 79 and 80 simultaneously with the contactors.

Resistances r_6 and r_7 are for the same purpose and function in the same manner as r , r_1 , 70 r_4 and r_5 .

Although compressed air is generally used for maintaining the piston in the cylinder in a raised position to keep the contactor closed, it is obvious that any suitable fluid under pressure may be used for the same purpose. 75

While I have shown only one embodiment of my invention for the purposes of illustration and description, it will be apparent to those skilled in the art that other changes and modifications may be made without departing from the scope of the invention. I, therefore, desire to be limited only by the scope of the appended claims. 80

I claim:

1. An electromagnetic release valve adapted for use with a fluid-actuated device comprising a valve and valve seat, a spring surrounding the valve stem for actuating said valve, an electromagnet, an armature having a sleeve portion extending slidably through the core of said magnet and abutting said spring, said valve stem extending slidably through said sleeve, and means on the end of said valve stem for varying the pressure of said sleeve on said spring to impart initial compression thereto, said electromagnet being adapted to impart final compression to said spring to actuate said valve. 90

2. An electromagnetic release valve adapted for use with a fluid-actuated device comprising a valve and valve seat, a spring surrounding the valve stem for actuating said valve, an electromagnet, an armature having a sleeve portion extending slidably through the core of said magnet and abutting said spring, said valve stem extending slidably through said sleeve, means on the end of said valve stem for carrying the pressure of said sleeve on said spring to impart initial compression thereto, said electromagnet being adapted to impart final compression to said spring to actuate said valve, and a second spring acting on said sleeve portion to urge said armature to within tractive range of said electromagnet. 100

3. A device adapted for use with a fluid-actuated device of the type comprising an electromagnetic valve for controlling the ingress and egress of fluid, said device comprising a release valve serving to hasten the egress of air to quicken the action of said fluid-actuated device, and means for rendering said electromagnetic valve inoperative until said release valve is in its normal position. 110

4. A device adapted for use with a fluid-actuated device of the type comprising an electromagnetic valve for controlling the ingress and egress of fluid, said device comprising

ing a release valve serving to hasten the egress of air to quicken the action of said fluid-actuated device and a switch operable by said release valve for rendering said electromagnetic valve inoperative until said release valve is in its closed position.

5. An electromagnetic release valve adapted for use with a fluid-actuated device for opening and closing an electrical circuit comprising a valve and valve seat, an electromagnet for actuating said valve, said electromagnet comprising a shunt coil for energizing the same and a series coil for energizing said magnet in opposition to energization 10 by said shunt coil, said series coil being connected across an inductive shunt in said circuit, whereby the armature of said electromagnet may be released in the event of abnormal load current flow in said circuit.
